CLAIM

We claim the ornamental design for an information handling system display device, as shown and described.

DESCRIPTION

FIG. 1 is a front perspective view of the information handling system display device comprising the present invention;

FIG. 2 is a front view thereof;

FIG. 3 is a top view thereof;

FIG. 4 is a bottom view thereof;

FIG. 5 is a side view thereof;

FIG. 6 is a back view thereof; and,

FIG. 7 is an opposite side view thereof.

Broken lines shown in the drawings illustrate portions of the information handling system display device and form no part of the claimed design.
